CLAIM

The ornamental design for a lancing device, as shown and described.

DESCRIPTION

FIG. 1 is a perspective view of a lancing device according to a preferred form of the present design.

FIG. 2 is a top view of the lancing device of FIG. 1.

FIG. 3 is a bottom view of the lancing device of FIG. 1.

FIG. 4 is a first side view of the lancing device of FIG. 1.

FIG. 5 is a second side view of a lancing device of FIG. 1.

FIG. 6 is first end view of the lancing device of FIG. 1; and,

FIG. 7 is a second end view of the lancing device of FIG. 1.
